Attorney

UNITED STATES PATENT OFFICE.

JOSEPH F. SCHMIDT, OF WALTERS, MINNESOTA.

DESIGN FOR A SLEIGH-KNEE FOR HEAVY VEHICLES.

59,935.

Specification for Design.

Patented Dec. 6, 1921.

Application filed January 8, 1921. Serial No. 435,997. Term of patent 7 years.

To all whom it may concern:

Be it known that I, JOSEPH F. SCHMIDT, a citizen of the United States, residing at Walters, in the county of Faribault and State of Minnesota, have invented a new, original, and ornamental Design for a Sleigh-Knee for Heavy Vehicles, of which the following is a specification, reference being had to the accompanying drawing, forming part thereof.

Figure 1 is a side view of a sleigh knee for heavy vehicles showing my new design. Fig. 2 is a plan view, and Fig. 3 is an end view of the same.

The design comprises a horizontal, tubular and conical member of relatively great length in proportion to its diameter, a ver-

tical member having convex sides and arranged at substantially one-third of the length of the conical member from its larger end, a forked member at the free end of the vertical member, and a diagonal member extending between one side of the free end portion of the vertical member and the smaller end portion of the conical member and forming a triangular opening with the horizontal and vertical members.

I claim:

The ornamental design for a sleigh knee for heavy vehicles, as shown and described.

In testimony whereof I have affixed my signature.

JOSEPH F. SCHMIDT.
